UNITED STATES PATENT OFFICE.

HIRAM STEVENS MAXIM, OF STREATHAM, LONDON, ENGLAND, ASSIGNEE TO VICKERS
LIMITED, OF WESTMINSTER, ENGLAND.

BOMB FOR USE WITH AEROPLANES AND OTHER FLYING-MACHINES.

1,052,606.

Specification of Letters Patent.

Patented Feb. 11, 1913.

Application filed July 26, 1912. Serial No. 711,626.

To all whom it may concern:

Be it known that I, HIRAM STEVENS MAXIM, a subject of the King of Great Britain, residing at Sandhurst Lodge, Streatham, 5 in the county of London, England, have invented certain new and useful Improvements in or Relating to Bombs for Use with Aeroplanes and other Flying-Machines, of which the following is a specification:

This invention relates to bombs for use in connection with aeroplanes and other flying machines and particularly to bombs of the character in which a detonating charge 15 is retained in a tail tube in a position remote from the main charge until the bomb is discharged or released; the chief object being to insure the immunity of the bombs from premature or accidental explosion and 20 to insure the safety of the aviator, without impairing the efficiency of the working or the destructive effect of the bombs.

According to this invention the detonating charge is associated with a pole or tubular member which, when the bomb is discharged or released, is adapted to move relatively to the bomb to bring the detonating charge out of the tubular extension or tail piece into position for firing the main 25 charge when the extremity of said pole or tubular member strikes the ground, object or target.

When the bomb is attached to the aeroplane or flying machine the pole or tubular member is locked in such a manner that the 35 position of the detonating charge is outside or remote from the body of the bomb containing the main charge, and the detonating charge is only brought into position for firing the main charge after the bomb is released from the flying machine for the purpose of destruction, either during the fall or on impact.

In order that the said invention may be 45 clearly understood and readily carried into effect I will proceed to describe the same with reference to the accompanying drawings, in which—

Figure 1 is an elevation showing the improved bomb attached to the aeroplane or flying machine. Fig. 2 is a section of the fore part of the bomb taken along the axial

line thereof. Fig. 3 is a section of the extension or tail piece of the bomb taken along the axial line thereof. Fig. 4 is a plan view 5 of the firing pin shown in Fig. 2. Fig. 5 is an elevation showing a modified form of the bomb attached to the aeroplane or flying machine. Fig. 6 is a section of the pole or tubular member pertaining to the bomb. 6 Fig. 7 is a section of the main body of the bomb taken along the axial line thereof.

Referring to the arrangement illustrated in Figs. 1 to 4, the detonating charge *a* is carried by a tube or rod *a'* which is capable 3 of sliding in a tail piece *a''* formed or provided on the bomb casing *a''*. The tube *a'* is, however, secured from moving in the tail piece *a''* while the bomb is secured to the flying machine, by means of a pin or the 7 like *b*, which passes transversely through the tail piece *a''* and the tube *a'*; the said pin *b* being carried by the frame *b'* of the aeroplane or flying machine and being preferably hinged to the said frame. The bomb 7 is attached to the frame *b'* of the aeroplane or flying machine by means of a sliding bolt *b''* adapted to engage in eyes or lugs *b'''* formed or provided on the casing or shell *a''* of the bomb; the bolt being operated by 8 means of a lever *c* or equivalent device mounted on the flying machine conveniently to the aviator. When the bomb is released, the tail piece *a''* thereof falls clear of the pin *b* by which the tube *a'* or detonating 8 charge carrier was held, allowing the latter to slide in the said tail piece forwardly of the bomb with the result that the detonating charge *a* assumes a position inside the bomb casing *a''*, Fig. 2. A firing pin *c'* is secured 9 in the tail piece *a''* being carried by an arm *c''* under the control of a spring *c'''* so that while the tube or pole *a'* is locked in the tail piece *a''* (before release, Fig. 3), the said spring controlled arm *c''* pertaining to the 9 firing pin *c'* is supported by the said tube or pole *a'* but when the latter moves forward and the detonating charge *a* enters the bomb casing *a''* as shown in Fig. 2 the firing pin *c'* owing to the action of the spring *c'''* and a 10 suitable stop *c''* if found necessary assumes a position in the interior of the tail piece *a''* and in line with a primer *d* on the detonating charge *a*. It will be understood that the

mb casing a^3 is provided with a central
ular passage d' in and through which the
oresaid tube or pole a' resides and passes.
The forward end of the pole or tubular
mber a' is provided with a nose or termina-
tion d^2 which normally projects from the
ward end of the bomb casing a^3 ; when
the bomb is released its travel is retarded by
table means hereinafter referred to, so
to allow the said member a' to slide for-
ward under the greater or unretarded in-
ence of gravity and project to its full ex-
t from the bomb casing. Thus the deto-
ning charge a is brought to rest slightly
ward of the firing pin c' Fig. 2 so that
en the forward end of the tube a' strikes
ground, object, or target it is forced in-
ward and causes the primer d to come vio-
lently into contact with the firing pin, firing
detonating charge a and exploding the
in charge d^3 in the bomb casing a^3 before
the bomb actually reaches the ground. The
height from the ground at which the explo-
sion occurs may be varied by varying the
length of the tube a' or by telescoping the
tube or otherwise providing for its exten-
sion.

For the better direction and stability of
the bomb during its passage through the air,
when released from the flying machine,
straps or webs d^4 are fitted to the tail piece
and a parachute or the like may be se-
wed to the said webs by the cords d^5 for
controlling the descent or forward movement
by gravitation of the bomb casing a^3 and tail
piece a^2 so that the firing mechanism per-
taining to the bomb may be enabled to as-
sume the required position for rendering
the same operative. The parachute may
consist of a sheet of canvas or other mate-
rial suitably secured to the tail of the bomb.
In some instances, the pole or tubular
member may be constructed in such a man-
ner as to be capable of automatically extend-
ing, for instance, telescopically during the
descent of the bomb. Such an arrange-
ment is shown in Figs. 5 to 7 and in this
, the tube a' is constructed in sections a^6
decreasing diameter in a manner well un-
derstood, all the sections being adapted for
being held in the collapsed position by the
firing pin b carried by the flying ma-
chine (Fig. 7). Spring catches a^7 or the
like are provided so that as the tube a'
automatically extends during the descent of
the bomb the sections of the tube are locked
in the extended position. In this construc-
tion the firing pin c' is arranged within the
bomb casing a^3 and the detonating charge a
is situated in the beforementioned telescopic
tube a' externally to and forward of the
bomb casing a^3 and when the device is re-
leased from the flying machine the telescopic
tube a' extends by the unretarded effort of
gravity while the travel of the bomb proper

is retarded by the aforesaid retarding means.
As a result, the detonating charge a is held
just forward of the bomb casing a^3 and
upon the nose or forward extremity d^2 of
the telescopic tube or pole a' striking the 70
ground, the detonating charge a is driven
into the bomb casing against the firing pin
and exploded, thereupon igniting the main
charge d^3 and exploding the bomb.

What I claim and desire to secure by Let- 75
ters Patent of the United States, is:—

1. In a bomb for use with aeroplanes and
other flying machines the combination of a
casing, a charge of high explosive in said
casing, an extension on said casing, a deto- 80
nating charge in said extension remote from
the main charge and a pole which is adapted
to move relatively to the bomb when the
latter is liberated, to bring the detonating
charge out of said extension into position 85
for firing the main charge upon the extrem-
ity of said pole striking the ground, object
or target.

2. In a bomb for use with aeroplanes and
other flying machines the combination of a 90
casing, a charge of high explosive in said
casing, an extension on said casing, a deto-
nating charge in said extension remote from
the main charge and a tubular member asso- 95
ciated with said detonating charge which
when the bomb is liberated is adapted to
move relatively to the bomb to bring the
detonating charge out of said extension into
position for firing the main charge when 100
the extremity of said tubular member strikes
the ground, object or target.

3. In a bomb for use with aeroplanes and
other flying machines the combination of 105
a casing, a charge of high explosive in said
casing, an extension on said casing, a deto-
nating charge in said extension remote from
the main charge, a pole associated with said
detonating charge which when the bomb is 110
liberated is adapted to move relatively to
the bomb to bring the detonating charge out
of said extension into position for firing the
main charge and a firing pin which is auto-
matically brought into the operative pos- 115
ition when the aforesaid movement of the
detonating charge takes place and which is
adapted to fire said charge when the ex-
tremity of the pole strikes the ground, ob-
ject or target.

4. In a bomb for use with aeroplanes and
other flying machines the combination of a 120
casing, a charge of high explosive in said
casing, an extension on said casing, a deto-
nating charge in said extension remote from
the main charge, a tubular member associ- 125
ated with said detonating charge which when
the bomb is liberated is adapted to move rela-
tively to the bomb to bring the detonating
charge out of said extension into position
for firing the main charge and a firing pin 130
which is automatically brought into the op-

erative position when the aforesaid movement of the detonating charge takes place and which is adapted to fire said charge when the extremity of the tubular member 5 strikes the ground, object or target.

5. In a bomb for use with aeroplanes and other flying machines, the combination of a casing, a charge of high explosive in said casing, an extension on said casing, a detonating charge in said extension remote from the main charge and a telescopic tube associated with said detonating charge which when the bomb is liberated is adapted to extend and move relatively to the bomb 10 to bring the detonating charge out of said extension into position for firing the main charge when the extremity of said telescopic tube strikes the ground, object or target.

6. In a bomb for use with aeroplanes and other flying machines the combination of a casing, a charge of high explosive in said casing, a tail tube on said casing, a detonating charge in said tail tube remote from the main charge and a telescopic tube associated 25 with said detonating charge which when the bomb is liberated is adapted to extend and move relatively to the bomb to bring the detonating charge out of such tail tube into position for firing the main charge when the 30 extremity of said telescopic tube strikes the ground, object or target.

7. In a bomb for use with aeroplanes and other flying machines the combination of a casing, a charge of high explosive in said casing, a tail tube on said casing, a detonating charge in said tail tube remote from the main charge, a telescopic tube associated with said detonating charge which when the bomb is liberated is adapted to extend and 40 move relatively to the bomb to bring the detonating charge out of such tail tube into position for firing the main charge, and a firing pin which is automatically brought into the operative position when the afore-

said movement of the detonating charge 45 takes place and which is adapted to fire said charge when the extremity of the telescopic tube strikes the ground, object or target.

8. In a bomb for use with aeroplanes and other flying machines the combination of a 50 casing, a charge of high explosive in said casing, a tail tube on said casing, a detonating charge in said tail tube remote from the main charge, a telescopic tube associated with said detonating charge which when the 55 bomb is liberated is adapted to extend and move relatively to the bomb to bring the detonating charge out of such tail tube into position for firing the main charge, means for retaining said telescopic tube in its extended position and a firing pin which is automatically brought into the operative position when the aforesaid movement of the detonating charge takes place and which 60 is adapted to fire said charge when the extremity of the telescopic tube strikes the ground, object or target.

9. In a bomb for use with aeroplanes and other flying machines the combination of a 65 casing, a charge of high explosive in said 70 casing, an extension on said casing, a detonating charge in said extension remote from the main charge, a telescopic tube associated with said detonating charge which when the bomb is liberated is adapted to extend, means for retaining said telescopic tube in its extended position, and a firing 75 pin toward which the extended telescopic tube and detonating charge move bodily when the extremity of the tube strikes the 80 ground, object or target.

In testimony whereof I affix my signature in presence of two witnesses.

HIRAM STEVENS MAXIM.
